US0D1047138S

(12) **United States Design Patent** (10) Patent No.: **US D1,047,138 S**
(45) Date of Patent: ** Oct. 15, 2024

(54) **PORTABLE INJECTION DEVICE**

(71) Applicant: **NEMERA LA VERPILLIERE**, La Verpillière (FR)

(72) Inventors: **Guillaume Cerqueira**, Lyons (FR); **Julien Roux**, Grenoble (FR); **Marc Todesco**, Tignieu-Jameyzieu (FR); **Sébastien Delvalac**, Lyons (FR)

(73) Assignee: **NEMERA LA VERPILLIERE**, La Verpillière (FR)

(**) Term: **15 Years**

(21) Appl. No.: **35/513,345**

(22) Filed: **Dec. 21, 2021**

(80) **Hague Agreement Data**

Int. Filing Date: **Dec. 21, 2021**

Int. Reg. No.: **DM/218054**

Int. Reg. Date: **Dec. 21, 2021**

Int. Reg. Pub. Date: **Jan. 7, 2022**

(51) **LOC (14) Cl.** **24-02**

(52) **U.S. Cl.**

USPC **D24/113**

(57) **CLAIM**

The ornamental design for a portable injection device, as shown and described.

DESCRIPTION

1.1 is a top perspective view of our design;

1.2 is a back view thereof;

1.3 is a front view thereof;

1.4 is a right view thereof;

1.5 is a bottom perspective view thereof;

1.6. is a top view thereof;

1.7. is a bottom view thereof;

1.8. is a left view thereof.

The dashed broken lines represent portions of the article that form no part of the claimed design. Dotted broken lines represent a change in the slope of a surface and form no part of the claimed design.

1 Claim, 8 Drawing Sheets
